FACEPLATE AND RECEPTACLE WITH PRONG
GUIDING MEANS

William C. Holden, Ossining, N. Y.

Application September 14, 1939, Serial No. 294,967

5 Claims. (Cl. 174—66)

This invention relates to electric connecting devices having guiding means to facilitate the insertion of the prongs of an attachment plug cap in the prong slots of the connector. More particularly it relates to a combination of a faceplate and attachment plug receptacle having guiding means to assist the prongs of an attachment plug cap to enter the contact apertures or slots of the receptacle.

10 It is an object of my invention to simplify and to provide a more effective means to guide the prongs of an attachment plug into the apertures of a receptacle. Other objects and advantages of my invention will appear as it is described in connection with the accompanying drawing.

15 The difficulty one experiences in trying to insert the prongs of an attachment plug cap into the prong apertures or slots of a receptacle are well-known to all. Many attempts have been made to simplify the operation of inserting the prongs in their apertures by providing various forms of prong guiding surfaces but they have not been entirely successful for a variety of reasons. The common expedient has been to provide a barrier or elevated portion on the guiding surface between the prong apertures of the receptacle with the idea that when once the prongs were properly placed straddling this barrier, they could more easily be manipulated and inserted in the apertures. The difficulty with this attempt at solution of the problem arises from the fact that quite often the prongs are both placed on one side of the barrier and this causes a great deal of fumbling in an attempt to insert the prongs in their apertures. The difficulty which arises in the attempt to insert the prongs in their apertures is in most cases due to the fact that the receptacle is placed in a position where it cannot readily be seen and can only be reached with difficulty. Frequently the receptacle is behind furniture which it is inconvenient or difficult to move.

20 My invention solves the difficulty in a simple and effective manner in that it provides a guiding surface for the attachment plug cap prongs to their apertures in the receptacle and presents no barrier or impediment in the course of travel of the prongs into their apertures.

25 The invention herein is a modification, as applied to a receptacle faceplate, of the invention in my prior application Serial No. 243,789, filed December 3, 1938.

In the drawing—

30 Fig. 1 is a bottom view of a faceplate to which my prong guiding surface has been applied;

Fig. 2 is a plan view of a receptacle for use with the plate of Fig. 1;

Fig. 3 is a plan view of the plate and receptacle of Figs. 1 and 2 when assembled;

Fig. 4 is a longitudinal section view taken along line 4—4 of Fig. 3.

Referring to the drawing, the attachment plug receptacle may be of the duplex type, with duplicate spaced outlets 10 and 12 thereof in the usual form having slots or apertures 14 for the reception of prongs of an attachment plug cap. It will be understood by those skilled in the art that the slots 14 will contain, or have beneath them, contact fingers (not visible) to be engaged by the prongs of the attachment plug cap when the prongs are inserted in the slots. Preferably the top surfaces of the two outlets 10 and 12 will be in a single plane with a depression 34 between them. The receptacle may have a main body part 16 and a bottom cover 18 secured thereto by a rivet 20 passing centrally through the cover and body. The rivet may have a hollow end internally threaded to receive a screw 22 which passes through a central opening 24 in the rectangular faceplate 26 whereby the faceplate and receptacle may be secured together.

The faceplate 26 may be made of any suitable material but molded insulating material is preferred. The faceplate is provided with a pair of circular openings 28 and 30 whose diameters are equal and are also approximately equal to the distance between the outer sides of a pair of receptacle slots 14 of the receptacles. The plate 26 is so positioned that the openings 28 and 30 lie over the slots 14 so that the prongs of an attachment plug cap may be inserted in the slots through the circular openings 28 and 30. In order to properly position the plate and the openings 28 and 30 over the receptacle outlets 10 and 12, there may be provided on the bottom surface of the face plate 26 a rectangular projection 32 which is adapted to fit snugly in the space 34 between the outlets 10 and 12 and thus prevent longitudinal movement of the faceplate relative to the receptacle. Lateral movement of the faceplate relative to the receptacle may be prevented by providing a pair of parallel ribs 36 and 38 extending along the bottom surface of the faceplate toward the end from the openings 28 and 30. These ribs 36 and 38 may be spaced so as to lie along opposite side edges of the bend adjacent the end portion of the conventional metallic supporting bridge 40 of the receptacle. The screw 22 also comprises an important means for maintaining the position of the plate with 55

relation to the receptacle since when the screw is inserted it holds the faceplate and receptacle together, while either the extension 32 or the ribs 36 and 38 cooperating respectively with the receptacle or the supporting bridge will prevent 5 rotation of the plate upon the receptacle.

The means to guide the prongs of the attachment plug cap into the slots 14 consists primarily in a circular concave surface 42 around 10 each of the openings 28 and 30 and extending downwardly from the surface of the faceplate to those openings. Secondary guidance of the prongs is accomplished by the openings 28 and 30, which due to the natural thickness of the plate 26 form wells at the bottom of the guiding surfaces 42 so that once the prongs have slid down the guiding surfaces into the openings 28 and 30, the vertical walls of these openings act as stop means and tend to keep the prongs within 15 the openings. Thereafter a simple twisting motion, which one ordinarily makes in attempting 20 to insert the prongs of a plug cap into a receptacle, serves to bring the prongs in register with the prong apertures. It is desirable for the vertical walls of the wells to be of greater height 25 than the usual bevel or rounding of the corners of the prongs of an attachment plug cap, so that the prongs may not cam themselves over the edges of the well and up again onto the guiding surface 42. The plate thickness at the wells 30 will be determined with this desire in mind.

Preferably the guiding surface 42 will be made approximately equal in width (i. e., the distance from periphery of the opening 28 or 30 to the outer periphery surface 42) to the distance across 35 the prongs but this dimension may be varied as requirements of particular installations require. It is desirable, however, to have the diameter of the guiding surface 42 greater than twice the distance across the plug prongs. By making 40 the guiding surface of large extent, almost any attempt to insert the plug prongs in their slots will result in the prongs falling upon some portion of the surface 42, after which the concave characteristic of the surface will serve to guide 45 the prongs into the openings 28 or 30, whereupon the plug can be twisted and will be guided by the periphery of the opening (28 or 30) until the prongs are in register with, or fall into, the 50 slots 14. If desired, the faceplate and the receptacle body may be molded as one piece, or said faceplate and the top portion of the said receptacle may be molded in one piece.

From the foregoing, it will be apparent that I 55 have provided a simple and effective means for assisting the insertion of attachment plug cap prongs into the slots of a receptacle and that the means provided insures that any normal attempt to insert the prongs in their apertures will not be hampered by any protuberance or elevation on the guiding surface but, on the other hand, the guiding surface will always assist the 60 insertion of the prongs in their apertures.

Modifications within the scope of this invention will occur to those skilled in the art. Therefore I do not limit the invention to the exact form 65 as shown and described.

I claim:

1. A faceplate for an attachment plug receptacle body, said plate being pierced for the passage therethrough of the prongs of an attachment plug cap in order that said prongs may engage contacts in a receptacle body behind said faceplate, said plate having a concave surface 70 extending up from the pierced portion of said

plate to guide the plug prongs, said concave surface being of such extent that the least distance across it is in excess of twice the distance across the plug prongs, said concave surface being formed to present no impediment to the passage 5 of a prong across the said concave surface into said pierced portion.

2. A faceplate and receptacle combination constructed and arranged to assist the insertion of the prongs of an attachment plug cap into the receptacle, comprising a plate portion having a concave surface of such extent that the least distance across it is in excess of twice the distance across the plug prongs, in combination 10 with a receptacle portion cooperating with said plate portion in the central part of said concave surface, the adjoining parts of said plate and receptacle portions being constructed and arranged to form depressed means to entrap and to guide the prongs, as the prongs are turned, 15 into prong apertures in said receptacle portion, whereby said concave surface forms the original guiding means for the prongs and said entrapping means forms the final guiding means for the prongs, said entrapping means being formed 20 to present no impediment to the passage of a prong across it, and said concave surface being formed to present no impediment to the passage 25 of a prong over it into said entrapping means.

3. A faceplate and receptacle combination constructed and arranged to assist the insertion of the prongs of an attachment plug cap into the receptacle, comprising a plate portion having a concave surface of such extent that the least distance across it is in excess of twice the distance across the plug prongs, in combination 30 with a receptacle portion cooperating with said plate portion in the central part of said concave surface, the adjoining parts of said plate and receptacle portions being constructed and arranged to form a round well having a diameter 35 approximately equal to the distance across the prongs and having walls substantially normal to said concave surface and serving to entrap and to guide the prongs, as the prongs are turned, 40 into prong apertures in said receptacle portion, whereby said concave surface forms the original guiding means for the prongs and said well forms the final guiding means for the prongs, said well being formed to present no impediment to the 45 passage of a prong across it, and said concave surface being formed to present no impediment to the 50 passage of a prong over it into said well.

4. A faceplate for an attachment plug receptacle body, said plate having an opening for passage therethrough of the prongs of an attachment plug cap in order that said prongs may engage contacts in a receptacle body behind said faceplate, the distance across said opening being approximately equal to the distance across the 55 prongs of an attachment plug cap and the walls of said opening forming a secondary guiding means for said prongs, said plate having a concave surface extending up from said opening to afford original guiding means for said prongs, 60 said concave surface being of such extent that the least distance across it is in excess of twice the distance across the plug prongs, said concave surface being formed to present no impediment to the 65 passage of said prongs across it into said 70 opening.

5. In an attachment plug receptacle device having means to guide the prongs of a plug cap into engagement with receptacle contacts, a faceplate having a concave surface across which the 75

least distance is in excess of twice the distance across the plug prongs, said concave surface affording original guiding means for said plug prongs, said concave surface running down to a central recess, the distance across said recess being approximately equal to the distance across the prongs of an attachment plug cap whereby

said recess functions to entrap said plug prongs and affords a secondary means to guide said plug prongs as said cap is manipulated in attempt to engage its prongs with the receptacle contacts.

WILLIAM C. HOLDEN.
